UNITED STATES PATENT OFFICE.

AUGUST KIECKHEFER, OF MILWAUKEE, WISCONSIN.

ELEVATOR.

SPECIFICATION forming part of Letters Patent No. 293,038, dated February 5, 1884.

Application for filed November 6, 1883. (No model.)

To all whom it may concern:

Be it known that I, AUGUST KIECKHEFER, of Milwaukee, in the county of Milwaukee and State of Wisconsin, have invented certain new and useful Improvements in Elevators; and I do hereby declare that the following is a full, clear, and exact description thereof.

My invention relates to balance-elevators for buildings, and will be fully described hereinafter.

In the drawings, Figure 1 is a vertical section of my improved elevator. Figs. 2, 3, 4, and 6 show details of the same; and Fig. 5 is a partly-broken side elevation of said elevator.

15 A is the car, which, by means of the usual wire cables, *a*, passing over the sheaves *b b*, properly mounted above top of well-room *B*, is connected to the counter-balancing bucket *C*. This bucket *C* runs the whole height of the building between the posts *c c*, either close to the elevator-well, or at any distance from it, as may be desirable, and it is guided along said posts *c c* by means of the notched bearings *c'*, formed in its flanged top *c'* and bottom *c'*. Said bucket *C* is attached, in any desirable manner, to the wire cables *a*, and it is weighted, so as to counterbalance the weight of the empty car *A* or of the platform used in place of said car.

30 In its bottom *f* of said bucket is formed an opening, *g*, and just above said opening is fitted the valve *D*, of any suitable form, to one of the bearing-trunnions *h* of which is keyed on the weighted lever-arm *h'* to keep said valve closed. The weighted end of said arm *h'* is

35 provided with a hook, *h''*, whereon is attached the end of the valve operating wire cable *a'*. This wire cable *a'* runs over pulleys *b' b'* above well-room *B*, and thence, passing through the car-roof, reaches down to attach in the hook *h''* of a treadle, *c''*, properly mounted near the floor of said car *A*. A rubber strip, *c''*, is fitted around the flanged top and bottom of said bucket *C*, by means of which and of the cone-shaped pipes *E*, provided in the path of said

40 bucket *C*, through the top and bottom stories of the building, a cushion of compressed air is obtained above or below said bucket *C*, which will safely arrest the same when, from some accident or other, a sudden rise or fall of said bucket is inevitable. This stopping device is designed to act in connection with a similar one provided on the car *A* itself. Rubber

strips *d d* are fastened around the top and bottom of said car *A*. As said car ascends or descends, said rubber strips come in juxtaposition with the sides *B'* of the well, which, in the top and basement stories, are given a proper incline for that purpose, this disposition preventing the air from escaping above or below the car, as the case may be. The sudden rise 60 or fall of said car is timely arrested by the air-cushion thus produced.

The hoisting or lowering of the loaded car is obtained by means of lead shot, a certain supply of which is constantly or intermittently 65 fed to the hopper *E'* by a bucket-belt elevator, *F*, from the boot *G*. On the shaft *g'* of the belt-wheel is mounted the pulley *g''*, which is connected by proper belting with the driving machinery.

70 The hopper *E'* is provided in its bottom opening with the valve *D'*, similar to the valve *D* of bucket *C*, and said valve *D'* is controlled by the wire cable *a''*, which, as the wire *a'* may be run over pulleys or be cut to connect to both ends of a lever, *H*, fulcrumed on top of standard *H'* in the attic, said wire *a''* runs down thence, passing through the car, to the bottom of the well-room *B*, where it is attached to a hook, *a''*, in the floor.

80 Along the post *J*, on one or each side of the well-room, I fasten a flat iron bar, *K*, which projects enough in the well to come in the path of a clutch-brake, *L*, carried underneath the car or platform. Said clutch-brake *L* consists 85 of the crank-shaft *m*, journaled in bracket-hanger *M'*, bolted onto the under side of cross-bar *M* of the car-bottom. Said crank-shaft is provided with a right-and-left screw-thread for the threaded sleeves *n n* of levers *N*, working against each other on their slotted fulcrum *o*, over a common hinging-bolt, *P*, depending from said cross-bar *M*. Said levers *N* are widened in their free ends *n' n'*, to give them the proper degree of friction necessary to stop the motion of the car, as by means of the hand-lever *p*, connected to said crank-shaft *m* by link *m'*; the conductor of said car forces said free ends *n' n'* against said bar *K*.

95 From the above description the operation of my improved balance-elevator is readily understood. The hopper *E'* being kept supplied with the proper quantity of lead shot by means of the elevating-bucket belt *F*, driven by the

engine, the valve D in the bottom of said hopper is opened by the conductor through wire cable a^2 until the proper amount of shot has run into the bucket C to raise the car A, 5 which, by means of the hand-lever p , actuating the clutch-brake L against brake-bar K, can be stopped at either of the floors of the building. The descent of the car is obtained by the opening of the valve D of said bucket 10 C through the wire cable a' , connected to the treadle a' , within reach of the conductor's foot, the shot emptying from said bucket into the boot G of the elevating-belt F until the living weight of the car overbalances said bucket. 15. I am aware that heretofore the basement of the well-room has been constructed so as to secure an air-compressing chamber with the cushioned sides of the car-bottom; but I claim as new the fitting of a similar compressing- 20 chamber in the top story of said well-room, and providing elastic cushions along the sides of the car-top for that purpose.

Having thus described my invention, what I claim as new, and desire to secure by Letters Patent, is—

1. In an elevator, a counterbalancing-bucket, C, adapted to rise and fall in vertical ways, properly connected to the car or platform, and adapted to raise or lower the same respectively as the proper weight is emptied in said bucket from a valve-controlled hopper in the top of the building or emptied from said bucket through a valve in its bottom, as set forth.

2. In an elevator, a well-room having the 35 sides of its top story inclined inward toward the ceiling, wherein a sufficient volume of air may be compressed by means of elastic strips fitted on the corresponding sides of the car-top to gradually arrest the sudden rise of the 40 car, due to a breakage of some part of the hoisting mechanism or to some other accident, in combination with the similarly-inclined sides of the well-room basement and the elastic strips fitted on the sides of the car-bottom, as set forth.

3. In an elevator, the counterbalancing-bucket C, having notched bearings c' in its top and bottom, and the automatic valve D, in combination with the bucket-belt elevator F, 50 having the boot G and the valve-controlled

hopper E', substantially as shown and described, and for the purpose set forth.

4. In an elevator, the bucket C, filled with shot C', in combination with the wire cables a , the sheaves b b , and the car A, substantially 55 as shown and described, and for the purpose set forth.

5. In an elevator, the clutch-brake L, consisting of right-and-left-threaded crank-shaft m of articulated levers N, having threaded sleeves n n , slotted fulcrum o , and clutching-arms n' n' , both supported by bracket-hanger M', and fulcrum-hinging bolt P on cross-bar M, in combination with flat iron bar K of post J, connecting rod or link m' , and hand-lever 60 p , substantially as shown and described, and for the purpose set forth.

6. In an elevator, the inclined sides B' of the well-room top story and the elastic strips d' along the sides of car-top A', in combination 70 with the inclined sides B' of the well-room basement story, and the elastic strips d' along the sides of the car-bottom A'', substantially as shown and described, and for the purpose set forth.

7. In an elevator, the inclined sides B' of the well-room top story and the elastic strips d' on sides of car-top A', in combination with the wires a , sheaves b b , the funnel-shaped pipes E, fitted in the basement story on the 80 path of counterbalancing-bucket C, having elastic strips c' around its bottom, substantially as shown and described, and for the purpose set forth.

8. In an elevator, the funnel-shaped pipe 85 E, fitted in the top story on the path of the counterbalancing-bucket C, having the elastic strip c' around its top, in combination with the inclined sides B' of well-room basement, and the elastic strips d' on the sides of the car-bottom, substantially as shown and described, and for the purpose set forth.

In testimony that I claim the foregoing I have hereunto set my hand at Milwaukee, in the county of Milwaukee and State of Wisconsin, in the presence of two witnesses.

AUGUST KIECKHEFER.
